UNITED STATES PATENT OFFICE.

CHARLES F. MCGLASHAN, OF TRUCKEE, CALIFORNIA.

CATAPULT FOR THROWING PROJECTILES.

SPECIFICATION forming part of Letters Patent No. 629,044, dated July 18, 1899.

Application filed December 2, 1898. Serial No. 698,089. (No model.)

To all whom it may concern:

Be it known that I, CHARLES F. MCGLASHAN, a citizen of the United States, residing at Truckee, county of Nevada, State of California, have invented an Improvement in Catapults for Throwing Projectiles; and I hereby declare the following to be a full, clear, and exact description of the same.

My invention relates to an improved apparatus for hurling projectiles, and is especially designed for the throwing of projectiles containing dynamite or other explosive compound, which it is desirable to throw without concussion or jar of any kind.

The invention consists in the parts and the constructions and combinations of parts hereinafter described and claimed.

Figure 1 is a general view of the catapult. Fig. 2 shows it with two springs. Fig. 3 is a view of a telescoping throwing-arm. Fig. 4 shows the manner of bringing the arm back. Fig. 5 is a detail of the holding and tripping device. Fig. 6 is a detail of the cup and connections. Fig. 7 is a modification of the same. Fig. 8 shows the employment of a spiral spring. Fig. 9 is a plan view showing a plurality of spiral springs in connection with a coil-spring.

The object of my invention is to so improve that class of apparatus known as "catapults" as to make them available for throwing bombs or other projectiles and in so constructing them that the trajectory and distance to which the projectile is thrown may be accurately estimated and gaged, so that the operator can accurately determine the point to which any projectile of a given weight will be hurled by the apparatus.

In carrying out my invention I employ one or more coiled or spiral springs or a combination of a plurality of either or both of these forms of springs. These springs are made of steel of any suitable or desired diameter, depending upon the power required, and they are coiled into proportionately large coils when used in this form or into spirals when used in the form of spiral springs. They may be combined in various forms, but I shall here describe such a construction and combination as have been proved by experiment to be very efficient.

A A are springs which are coiled, as shown in the present case, right and left, having

long arms or continuations B at their adjacent ends and shorter arms or projections C from the opposite ends of the coil. A base 55 or support of any suitable construction is employed and the shorter arms C are secured to this base. These arms are here shown as projecting at approximately right angles from the longer arms B, so that when the short 60 arms have been secured to the base by hooks or clamps of any description the longer arms B will project upwardly in an approximately vertical position. These longer arms lie close together and may be connected or secured so 65 as to move in unison by means of bands or fastenings b. The arms B may be made of any suitable or desired length, and one may be made longer than the other, so as to lighten the weight at the outer end, or if the length 70 is to be greatly increased, in order to give a higher velocity and longer sweep to the arm, the extension may be made tubular, as will be hereinafter more fully described. At the outer end of the throwing-arm is a cup, which 75 is designed to contain the projectile, which will also be hereinafter described.

The coil-springs are mounted as follows: Standards D are fixed upon the base I, and steel shafts a are supported in these standards, extending horizontally through the coils. The shafts are preferably covered or coated with some soft material, as leather, rubber, or other material, and exterior to them are fitted the cylindrical tubular sleeves a'. 80 These sleeves are sufficiently larger than the shafts to fit over the intermediate packing and are sufficiently smaller than the interior of the coils to allow of a similar covering or packing to be fitted over the sleeve. The 85 ends of the sleeves are formed as shown at a' and are bored of a sufficient size to receive the interior shafts a and to hold them central within the sleeves. The sleeves themselves form cushions for the coils and are in turn 90 cushioned upon the material surrounding the inner shaft, the object being to prevent the noise and to absorb the vibration caused by the sudden movement and recoil of the springs when the arms are released. By this construction I am enabled to operate the device, when composed of very large and strong 95 springs, without the use of any stop or bumper, as the oscillation and vibration are absorbed 100.

by this interior construction and noise is prevented.

If it is desired to extend the projectile-carrying arm to a great length and at the same time to reduce the weight so as not to impede its velocity, I construct the extensions of tubular sleeves V V' V^2 of decreasing diameter, so that one may fit inside of another. The end of the arm B will then be turned down and screw-threaded at each successive smaller diameter, as shown at B^2 B^3 , so that the sleeves V V' V^2 can be screwed upon these small offsets and thus extended, the inner one supporting the next in size, which may be made somewhat longer, and the outer one again being supported by the two and being longer than either of the interior ones, so as to make up the desired length without greatly increasing the weight. In order to bend these powerful springs and to bring the throwing-arm B into horizontal position, various devices may be used. I have shown a device which I call a "bending-bar" O . This bar is made of any desired length, having a suitable link or connection P for the attachment of a rope S , and this rope may pass around a windlass T or be operated by any other suitable or desired power, so as to pull the bending-arm O backward and downward. This arm O is connected with the throwing-arm B as follows: The arm O forks at the end adjacent to the springs, the forks curving outwardly beyond the ends of the springs A and having hooks R formed upon the ends of the forks, which are adapted to clasp the projecting ends of the shaft a . Q is a T-shaped rod, the shank of which extends up in line with the shank O , while the cross portion of the T has upturned arms, as shown, which are adapted to engage with the forks of the shank O near their point of junction. The cross-bar then rests upon the arm or arms B , and when, by means of the apparatus previously described, the shank O is pulled backwardly it carries the arms B with it. After these arms have been latched and secured the bending-bar and its attachments are removed, thus leaving the arms B ready to be released when necessary.

In order to hold the arm B in place when it has been drawn backward and downward, I have shown a trigger E , which is mounted upon a shaft E' , and this shaft is supported in standards F , fixed to the base-plate, as shown. The shaft E' is here shown as lying in the plane of movement of the arm B , and the trigger E thus swings transversely with relation to this plane. The upper ends of the standards F are here shown as being cut away, as shown at f , so as to allow the arm B to pass down into these openings and into line with the upper end of the trigger E . This trigger has a curved semicircular channel formed in its upper end, as shown at d , and when the arm B is brought down it strikes the beveled upper end of the arm E , swinging it temporarily out of the way until the arm B has

passed down opposite the semicircular groove d . The trigger then swings back so that the arm B is inclosed in this semicircular groove 70 or channel; but the upper part of the groove or channel is of such shape that unless the trigger were held in this position the pressure of the arm B would easily throw it back and release the arm. I have therefore shown a 75 tripping apparatus comprising a stop G , which is fulcrumed so that when the trigger E is in position to clasp and hold the arm B this stop G abuts against the lower end of the trigger and prevents its being swung so as to release the 80 arm B ; but as soon as this stop G is depressed below the end of the trigger it allows the trigger to swing and the arm to be released. This disengagement takes place by pressing upon the shank y , which carries the stop G , either 85 by the foot or by any suitable disengaging mechanism.

The cup or holder for the projectile is made as shown at J , and consists, essentially, of a frustum of a hollow cone, forming a tapering 90 ring of sufficient depth to give it the necessary strength and having its inner face essentially conical and without any bottom, so that when the projectile, which is preferably made globular, rests upon this ring it has only a 95 single line of contact with the surface of the ring. It is thus free to be easily disengaged and will not stick or be held by the ring, as I have found to be the case whenever the cup is made spherical or has a bottom or any continuous surface or support for the projectile. The inner surface of the ring is preferably 100 covered with some soft material sufficient to prevent any jar taking place when the projectile is placed upon the ring. This ring may 105 be supported from the bar B in various ways. In one form I have shown it made with a central shank f' projecting from one side and adapted to fit in a correspondingly-shaped groove or channel j , formed at the outer end 110 of the throwing-arm B . From the outer sides of the cup extend the bracing-arms g , which are parallel with the central arm F and extend exterior to the bar B , which is flattened at this point for the purpose. Through the 115 arms f' and g and the slotted end of the bar B holes are made, as shown at i , and a pivot-pin passes through these holes, so that the cup or ring J is turnable about the pivot-pin at I , and it may be adjusted with relation to the 120 arm B so as to stand either in a straight line with the arm or to be bent up to a position more nearly approaching right angles with said arm. The object of this construction is important, as it enables me, by the adjustment 125 of this cup with relation to the arm B , to determine the trajectory and the distance to which the projectile will be thrown.

In conjunction with this device I have shown a means for supporting the arm f' , 130 which may either an adjusting-screw k or the arm may be held by a pin and holding-segment, as will be hereinafter described.

In conjunction with this device I have shown

a scale l , which is fixed to the end of the bar B alongside of the arm f' and upon the radius of curvature from the pivot-pin i . This scale is laid out and determined by practical experiment and is marked so as to show the trajectory and range of projectiles of various weights with any given tension of spring which may be used. It is thus only necessary to set the arm f' at a given angle with the arm B , and which is indicated by the scale, to know exactly where a certain projectile will fall, and it can thus be as accurately calculated as the trajectory of any gun.

In order to verify the accuracy of the scale l , I have shown another scale m , fixed upon the projecting slotted end of the arm B and in conjunction with one of the brace-arms g , so that it may be used as a check in verification for the accuracy of the other scale. The bracing-arms g are especially important because of the tendency of the throwing-cup to break under the inertia when the spring is released.

Another manner of securing and adjusting the cup A is to make a cup with the extension f' , as previously described, and a similar extension f^2 upon the opposite and outward side of the cup. The inner extension f' is pivoted to legs q , which are held or fixed upon a sleeve P' . This sleeve fits around and upon the end of the arm B and is secured thereto by a rivet, pin, clamping-screw, or other suitable device. In line with the arm f' and at the outer end of the arm B is another clamp p' , similarly secured. Upon this sleeve is fixed the segment n , which is marked with a scale to indicate the angle to which the cup and its supporting-arms $f^2 f'$ should be set with relation to the arm B . In this case the segment n is perforated with small holes or provided with any other means for adjusting the arm f' , and the arm f^2 is slotted so as to fit over this segment, having holes made through its two parts, so that a pin can be passed through them and through the intermediate segment, and this will lock the arm f' to the segment at any desired point with relation to the scale which is marked upon the segment. The bracing-arms g in this case extend from the sides of the cup J in each direction and connect with the arms f' .

In some cases I have found it desirable to increase the strength of the apparatus by means of supplemental coil-springs A' . In this case the springs are journaled in a similar manner upon standards and shafts parallel with and at a short distance from the main coils. In Fig. 2 I have shown an arrangement of this sort in which the supplemental springs are journaled parallel with the main springs and sufficiently lower so as not to interfere with the depression of the throwing-arm B . In this case the supplemental springs have arms B' extending from the outer ends of the coils and converging to a point where they are to engage with the arm or arms B . At this point they are con-

nected by a grooved roller or rollers Z , which pass and lie beneath the arm B , so that when the springs are released the added force of the supplemental springs acts through the roller Z to force the arm B upward and forward. The coil-springs A' are in this case shown with the shorter arms C' projecting from the inner and adjacent ends of the coils, and they are bolted, clamped, or secured to the base or support in a manner similar to that previously described. As the two coils are not in the same line, it will be manifest that the movement of the arms B and B' will not entirely coincide. Consequently by means of the rollers Z this movement is allowed without any undue friction between the moving parts. I have also found that I can efficiently combine the coil-springs here shown with spiral springs disposed horizontally and acting in conjunction with the coil-springs, or I may employ the spiral springs independently, the action being essentially the same. In this case I have shown the standards D fixed to the base I in the manner previously described and an arm t fulcrumed between these standards. The long portion of this arm or lever serves as the throwing-arm and carries the adjustable cup in the same manner as previously described. The shorter arm is curved downwardly, so as to stand at an obtuse angle with the longer portion, and it has an attachment r for the coil-spring S' , this spring having its opposite end connected by any suitable powerful attachment with the base-plate. When the spring S' is closed together, the longer arm t will stand at an approximately vertical position in the same manner as described for the arms B when coil-springs are used. When the long arm is drawn down to the horizontal position by a suitable bending apparatus, the shorter arm will be carried backward between the standards D , and thus extend the coil-spring, so that its tension will act to throw the arm t through its arc with great velocity. If it is desired to increase the strength with this form of spring, it may be indefinitely increased by adding springs S^2 and connecting them with a common bar W , this bar then being connected by a yoke V with the shorter arm of the lever t . The spiral springs may also be combined with the coil-springs, as plainly shown in Fig. 9, the operation being essentially the same as previously described. In this case one or more spiral springs will have their ends anchored to the base and will be connected with the shorter arm of the lever t , which is journaled between the standards D . The coil-springs A' are similarly journaled in close proximity with the standards D , and in the present case I have shown them as lying beneath the arm t , which in this case is the throwing-arm. The arms B then carry the roller Z , which contacts with the arm t , and when the springs are released simultaneously the combined action takes place. The throwing-cup J is connected with the arm t in a manner similar to that previ-

ously described for its connection with the arm B, and the segment and catch may be constructed in a similar manner, the operation being essentially the same.

5 I have here described several forms in which my invention may be embodied and carried out, but I do not desire to limit myself especially to these forms, as I am aware that many modifications may be made of the apparatus 10 which will be essentially the same in practice as those which I have shown.

Having thus described my invention, what I claim as new, and desire to secure by Letters Patent, is—

15 1. An improvement in catapults consisting of a combination of coiled springs each having one end extended to form a fastening, and the other end extended at approximately right angles thereto to form a throwing-arm, and a 20 cushion interior to the springs to absorb the recoil of the latter.

2. The combination of one or more coiled springs having one end extended to form an anchor, the other end extended at approximately right angles thereto to form a throwing-arm, a journal-shaft extending centrally through the coils, exterior sleeves of larger diameter also extending through the coils intermediate between the interior thereof and 30 the shaft, and a packing or cushion material interposed between the shafts and sleeves, and between the latter and the coils.

3. The combination of one or more coiled springs having anchor-arms extending from 35 one end, throwing-arms from the other, journal-boxes and a shaft extending horizontally through the springs, an exterior sleeve of larger diameter having ends bored to fit the shaft and interior cushion material surrounding the shaft, and a second cushion material 40 interposed between the sleeve and the interior of the coils to absorb the recoil of the spring.

4. The combination with coil-springs having anchor and throwing arms as shown, of a 45 centrally-journalized shaft and an elastic cushion interposed between said shaft and the interior of the coils to absorb recoil and prevent noise.

5. In an apparatus of the character described, the combination of one or more coil-springs having anchor and throwing arms, a latch and trigger by which the throwing-arm is held in place when drawn into a horizontal 50 position, and a mechanism including an independent bending-bar fulcrumed upon the axis of the springs and a connection between said bar and throwing-arm for bending the arm to said position substantially, as described.

6. In an apparatus of the character described, one or more coil-springs having anchor and throwing arms projecting therefrom, a latch and trigger adapted to engage and hold the throwing-arm when the latter has been depressed to a horizontal position, a mechanism 60 for depressing the throwing-arm consisting of an independent bending-bar having arms or claws terminating in hooks adapt-

ed to engage the shaft of the coils, a connecting-bar to unite the bending-bar and throwing-arm and a device by which power may be applied to the bending-bar to draw it and the throwing-arm into a horizontal position and engage the latter with the trigger. 70

7. In an apparatus of the character described, one or more coils having anchor and throwing arms, means including an independent bending-arm fulcrumed on the axis of the coils and having a connection with the throwing-arm for bending the latter into a horizontal position, a latch and trigger for engaging, holding and releasing said arms, and a ring having a conical or beveled interior surface, said ring adjustably secured to the throwing-arm and adapted to receive the projectile. 75

8. In an apparatus of the character described, one or more coils having anchor and throwing arms, means including an independent arm fulcrumed on the axes of the coils for bending said throwing-arms into a horizontal position, and a latch and trigger for holding and releasing said arm, a projectile-containing cup secured to the outer end of the throwing-arm and means for lengthening said arm consisting of concentric tubes fitting 90 correspondingly-threaded differently-sized sections at the outer end of the solid arm, substantially as described. 95

9. In an apparatus of the character described, a plurality of coil-springs having anchor-arms projecting from the outer ends, throwing-arms projecting from the inner ends, a horizontal cushioned shaft extending through the coils and supports therefor and clamps whereby the adjacent throwing-arms 100 are united to form a single arm actuated by both the springs. 105

10. In an apparatus of the character described, one or more coil-springs mounted and operated as shown, a projectile-containing cup having arms and pivot-pin by which it is connected with the outer end of the throwing-arm in the plane of motion of the latter, a mechanism by which said cup is adjusted to stand at an angle with relation to the 110 throwing-arm, and a scale fixed with relation to said arms whereby the trajectory and distance of the projectile may be determined. 115

11. In an apparatus of the character described, the combination of one or more coil-springs having anchor and throwing arms, mechanism by which they are actuated and a second series of springs correspondingly constructed and journalized parallel with the first-named springs, arms connecting said 120 second series of springs with the throwing-arm of the first series whereby the combination of both sets of springs is applied to the throwing-arm of the first set. 125

12. In an apparatus of the character described, one or more sets of horizontally-supported springs parallel to each other having throwing-arms extending outwardly therefrom, and antifrictional rollers by which the 130

pressure of the second set of arms is communicated to the first set and movement longitudinally upon said arms is permitted.

13. In an apparatus of the character described, one or more anchored springs, a throwing-arm with which said springs are connected, a projectile-containing cup fixed to the outer end of the throwing-arm, means for adjusting said cup, and a scale fixed with relation to the cup to determine the angle to which said cup is adjusted, and means for combining a plurality of said springs and uniting them with the throwing-arm.

14. In an apparatus of the character described, the combination of coiled and spiral springs, throwing-arms having an adjustable projectile-containing cup at the outer end, and means for connecting the coil and spiral springs so that the two act in unison upon the throwing-arm.

In witness whereof I have hereunto set my hand.

CHARLES F. MCGLASHAN.
